(57) **CLAIM**

The ornamental design for light-emitting diode illuminating apparatus, as shown and described.

DESCRIPTION

FIG. 1 is a perspective view of a light-emitting diode illuminating apparatus showing my new design;

FIG. 2 is a front elevational view of the light-emitting diode illuminating apparatus;

FIG. 3 is a rear elevational view of the light-emitting diode illuminating apparatus;

FIG. 4 is a left side elevational view of the light-emitting diode illuminating apparatus;

FIG. 5 is a right side elevational view of the light-emitting diode illuminating apparatus;

FIG. 6 is a plan view of the light-emitting diode illuminating apparatus; and,

FIG. 7 is a bottom perspective view of the light-emitting diode illuminating apparatus.

The broken lines showing portions of the light-emitting diode illuminating apparatus are included for the purpose of illustrating non-claimed subject matter and form no part of the claimed design.
